CLAIM

The ornamental design of a jewelry article, as shown and described.

DESCRIPTION

FIG. 1 is an isometric view of an embodiment of a jewelry article illustrating the new design;
FIG. 2 is a front view thereof;
FIG. 3 is a rear view thereof;
FIG. 4 is a right-side view thereof;
FIG. 5 is a left-side view thereof;
FIG. 6 is a top-view thereof;
FIG. 7 is a bottom-view thereof;
FIG. 8 is an isometric view of another embodiment of a jewelry article illustrating the new design;
FIG. 9 is a front view thereof;

(Continued)

FIG. 10 is a rear view thereof;
FIG. 11 is a right-side view thereof;
FIG. 12 is a left-side view thereof;
FIG. 13 is a top-view thereof; and,
FIG. 14 is a bottom-view thereof.

The broken lines shown in the drawings represent portions of the jewelry article which form no part of the claimed design.

1 Claim, 12 Drawing Sheets
